UNITED STATES PATENT OFFICE.

CHARLES LA DOW, OF ALBANY, NEW YORK.

ELASTIC JOINT.

SPECIFICATION forming part of Letters Patent No. 691,571, dated January 21, 1902.

Application filed September 13, 1901. Serial No. 75,315. (No model.)

To all whom it may concern:

Be it known that I, CHARLES LA DOW, of the city and county of Albany and State of New York, have invented certain new and useful 5 Improvements in Joints, of which the following is a specification:

The object of my invention is to provide a simple and efficient means whereby a joint or connection may be made between a rod or 10 other member and a beam or other support for said member.

The drawings show the invention as applied to a spike-harrow.

Figure 1 represents a longitudinal section 15 of my invention. Fig. 2 represents a side elevation of Fig. 1. Fig. 3 represents a rear elevation of Fig. 1. Fig. 4 represents an elevation of the spring B. Fig. 5 represents a longitudinal section of Fig. 1, showing method 20 of attaching spring in position by instrument S, its double portion being broken away to expose the adjacent portion of the spring. Fig. 6 represents a longitudinal section of Fig. 1, showing means for adjusting the rod. 25 Fig. 7 represents a front perspective view of Fig. 1. Fig. 8 represents a horizontal section at line O, Fig. 1, showing rod removed. Fig. 9 represents a horizontal section taken at line O, Fig. 1, showing sectional view of rod 30 located in the saddle. Fig. 10 represents an instrument for applying the spring to the beam. Fig. 11 represents an enlarged longitudinal view showing the triangular position of the ends of the spring with reference to 35 the saddle-hinge x. Fig. 12 represents a plan view of a harrow-frame embodying my invention. Fig. 13 represents an end view of Fig. 12, showing by dotted lines some of the rods "locked" out of normal position. Fig. 14 40 represents a detail view showing a rod adapted to operate as shown in Fig. 13. Fig. 15 represents a longitudinal section with the saddle and rod made integral.

When the invention is to be used in harrows of the type shown, I prefer to use the commercial shape for a support for the teeth, known to the trade as a "U-beam," and for the teeth the ordinary square rod cut to proper length and sharpened; but other shapes can 45 be used.

Primarily the joint is designed to simply hold together in operative position under

spring tension a support and a rod or other parts or pieces of an article or implement; but as a refinement thereof the joint may be 55 also adapted to permit one part or piece thus held to be slid or adjusted lengthwise relatively to another part and there held in said adjusted position, and another refinement permits one part to rock relatively to another 60 part, and a still further refinement permits one part or piece to be held at different angles relatively to another part.

It will be observed that this joint in all forms of construction described operates on 65 the principle of lever and fulcrum, the lever thereof being in all instances illustrated a rod and the fulcrum the bearing on support C, said lever or rod preferably having rocking motion relative to support C; but when 70 the rod and its saddle are constructed as shown by dotted lines in Figs. 1, 2, and 11, so as not to rock, a "nip" is formed by the said rod, causing the projection b of the saddle to impinge at y against one limb of the channel-support and to also impinge at z against its other limb, thus forming another fulcrum 75 z, the said parts in this instance not having rocking relative movement because of the nip caused by said impinging construction. 80 When my joint is to be used in spike-harrows, said impinging construction enables a saddle and a rod to be constructed as shown in full lines in Fig. 1 and to rock or not to rock on its support C, as desired, said different results being produced by simply hauling a harrow of the usual frame construction from either end of said frame. When hauled from one end of the frame, the rods will rock, as shown in Figs. 2 and 13, when obstructions are met; but when the harrow is hauled from its opposite end, the rod-carrying saddle will nip with its frame C and the rod will 85 not rock, but will in such case operate as a rigid rod, having the advantage, however, of 90 being held under spring tension on support C without self-movement either laterally or transversely thereon and also having the further advantage of instantaneous adjustment 95 relatively to the spring, which in such instances becomes a spring performing all the functions hereinbefore described except that 100 of "rocking." For harrows I regard the rocking movement of the rod on its support as be-

ing far better than when held so as not to rock thereon, because the rocking movement described automatically sheds rubbish, avoids straining the implement-frame, or jerking the 5 team when obstructions are encountered.

In carrying out the invention as applied to harrows the rod A is carried by saddle B, which is mounted on support C and is there held in operative position by the spring D. 10 Working strains against the rod are minimized by its fulerum action, hereinafter explained.

The support C may be of such length, size, and form as will coact with the spring and 15 rod to produce any result hereinafter described.

The support C is of the well-known channel or U form. In the side thereof opposite the channel I roll, when the support is made, 20 a groove c, preferably V-shaped, into which one end of the spring D is seated and "bites" into said seat, but not sufficiently to prevent pivotal movement thereof in its seat.

The saddle B shown is of cast metal and 25 is made to carry the rod A. The saddle has a notch b', in which one end of the spring D is seated. The saddle may rock transversely in one direction on support C; but it has a projection b entering channel of support C 30 which impinges thereon at y and helps support the saddle from rocking on the support C in the opposite transverse direction. The saddle B may be constructed not to rock in either direction on support C. Then its 35 projection b fills the channel, as shown in dotted lines in Figs. 2 and 11. When constructed to rock on support C, said projection b is made as shown in full lines in Figs. 1, 2, and 11. When the saddle is constructed 40 to rock relatively to support C, it is advisably made to "wedge" or otherwise fit closely between the channel-limbs and to so abut or interlock with a channel-limb as to form a "stop," which prevents the rod or tooth 45 from "rebound" when the spring has been strained, and then quickly returns to normal position.

The material of which the spring D is made may be of any desired shape or size, but its 50 form should be substantially circular, with space between its ends sufficient to embrace and "self-grip" to the support C and saddle B. The spring in its primary form is shown in Fig. 4 as being made from round steel about

55 three-eighths of an inch in diameter, having its ends cut at right angles to its length, so that when bent into circular form it shall present a "corner" or "edge" adapted to bite into and self-grip into the groove c in 60 support C. The other end of the spring is similarly adapted to bite and hold the rod A in operative position relative to the saddle through which the rod passes. The spring D may be otherwise formed and still retain 65 the qualities of the one shown herein. The dotted lines in Fig. 4 show the expansion of the spring. The spring embraces the sup-

port and saddle and also that part of the rod which is adjacent to the saddle. The saddle may or may not rock on its support, according as the saddle is constructed, as hereinbefore described, without affecting the self-gripping action of the spring. 70

The rod A is adapted to be adjusted endwise in the saddle, but held from self-movement 75 therein by the end of the spring "biting" into the corner of the rod, which in this instance is square in cross-section. Said adjustment increases or lessens the leverage of the rod against the tension of the spring, according as the rod is slid and held relatively to the saddle. The spring can therefore be made to exert more or less pressure for different kinds of work, according as the length of the rod is adjusted under the spring. 80 85

The spring has sufficient power and is of such shape that its ends embed or indent themselves into their seats—viz., support C, as shown in Fig. 7, at c', and in rod A at a—sufficiently to prevent the spring from undesired movement in its groove c' lengthwise on support C and to prevent self-movement of the rod A in its seat in saddle B. 90

The saddle has a projection b² adjacent to notch b', which serves as a retainer against 95 which the end of the spring seated therein draws when strained without sliding the rod in the saddle.

The shape described for the end of the spring permits a screw-driver or other suitable instrument S (shown in Fig. 10) to be used as a lever to pry over fulerum b³ to lift the spring out of biting contact with the rod sufficiently to permit the rod to be slid in its seat under the spring without taking the 105 joint apart, as shown in Fig. 6. The rod may be removed and turned to a different position in its seat in the saddle without taking the joint apart. The rod may also be removed for shipment without removing the saddle or 110 spring, for in such instance the rod end of the spring then rests on a ledge or shoulder in the bottom of the notch in the saddle, as shown in Fig. 8, and thus without any rod under the spring holds the saddle to its beam 115 by pressing the saddle and support together between the ends of the spring, which then has direct contact with the saddle B and support C.

By reference to Fig. 1 it will be seen that 120 the contact-lines or relative supporting-bearings of the saddle support and spring are at lines 1, 2, and 3, in which instance the saddle need not rock. By reference to Fig. 11 it will be seen that the contact-points for the 125 saddle, support, and spring, the saddle being adapted to rock, are at a, c, x, y, and z. It will also be observed that the spring must first be expanded in order to locate it in position and to also cause it to exert force against 130 the rod sufficient for successful operation, and said expansion, which requires the application of considerable power, should be accomplished quickly and easily. This important

result I obtain by adapting the different parts in form and location so they shall assist each other in rendering this otherwise difficult task an easy one. To this end I loosely mount the 5 saddle in position on support C so that the saddle projection b will abut against beam C to hold the saddle from rocking in one direction and place one end of spring D in the saddle-notch and its other end adjacent to 10 the support C, as shown in Fig. 5. Then with an instrument (shown in Fig. 10) I pry the end of the spring which is to enter the groove c around the support C, using the rounded side of said support as a fulcrum for said instrument whereon to "rock" the spring around until the end thereof held by the instrument enters the groove c, when the spring 15 snaps into its seat c and the instrument may be removed. Other forms of instrument may 20 be used for this purpose; but the form shown operates satisfactorily.

When the joint is used for a rod for an agricultural implement and an obstruction stops the free end of the rod, which in the 25 form shown is known to the trade as being in itself a "rigid harrow-tooth," the progress of the implement is not checked; but the spring action of the joint permits the frame to advance until the rod slants backward 30 sufficiently to release itself from the obstruction, as shown by dotted lines in Fig. 2, when the rod instantly returns to its normal position, as shown in full lines in Fig. 2, with a "snap," caused by the efficient form of 35 spring I have described, and further assisted in said quick movement by the saddle rocking on one limb only of the U-support, thus avoiding the sluggish movement which would ensue because of greater friction if the saddle 40 rocked on a center coincident with the center of its support. The aforesaid quick return of the rod is instantly checked when a normal position is reached by the aforementioned stop action, and this peremptory 45 stopping of the rod's reaction materially assists in dislodging rubbish from an agricultural implement.

To prevent undue rocking movement of the free end of the rod, the saddle is provided 50 with a spur b³, which abuts against the exterior of support C simultaneously with the abutment of the hinge-corner x of the saddle projection against the interior of the channel-support, (shown in dotted lines in 55 Fig. 2,) thus forming another stop, but in an opposite direction and for a different purpose than the stop previously described. It will therefore be seen that the tooth is by the spring held to its work, but can rock and 60 act in predetermined limits.

Inasmuch as the rod, its saddle, and spring are supported at three points relatively to a fulcrum over which the rod may rock, the traveling or rod end of the spring is carried 65 by the rocking movement of the rod toward a straight line with reference to the center of motion around which it rocks. Therefore the

spring exerts greatest pressure against the rod's rocking movement when it is in its normal position, the said pressure being self-reducing as the rod end of the spring approaches a straight line with reference to the center around which it rocks. Fig. 11 illustrates this feature, the point a being the traveling end of the spring, c its pivotal end, x 70 its fulcrum, and z its rest, forming a highly efficient four-point bearing for the working parts. This variable pressure enables the free end of the rod or tooth to move above and out of rubbish frequently encountered 75 by agricultural implements and to clear it and other obstacles far better than if otherwise constructed. The aforesaid construction has the "holding-to-work" and "yielding" advantages of a "lock" spring-joint 80 without the great expense and size thereof. I may vary this pressure or lock action as desired by constructing the saddle-notch to locate the point a toward or from line 6, (shown in Fig. 11,) the rule being that the 85 nearer point a is brought toward line 6 the less will be the pressure from the spring against the rod, and vice versa; but point a should not pass line 4 only when it is desired to accomplish a special result, which I 90 will now describe and which is independent of the results previously described.

It is sometimes desirable to be able to hold the rod in another position relatively to its support than in the normal working position 95 heretofore described, and to accomplish such special result I form a notch L in the saddle projection b, as shown in Fig. 14, and I also cut away a portion of the saddle-stop at b³ in 100 said figure, which permits the saddle to rock 105 to such an extent relatively to its support that joint a passes line 4 and forms a dead-center or lock-joint relatively to fulcrum x. The spring follows and permits this movement and at the proper stage "locks" the 110 saddle and rod in the position indicated in dotted lines in said figure and continues to maintain them in said position until sufficient force is applied to the free end of the rod to break said lock-joint effect, when the spring 115 quickly returns the saddle and rod to normal working position, as hereinbefore described. The contact-bearings at c should be modified to accommodate this increased movement. Notch L and spring prevent disengagement 120 of abutting hinge portions when rod is "locked" up. This special result is very useful for many purposes and can be utilized in many kinds of articles and implements.

This joint is most conveniently mounted 125 and operated on a support having U form in cross-section; but it can be used with supports having other forms. The groove c may be omitted and a rib substituted, or a hole 130 may be made through support C, in which the non-traveling end of the spring may rest, or an indentation by chisel or center punch or other surface which is interrupted or made to be irregular in the direction in which the

spring is strained will in some instances provide a suitable seat for the said end of the spring. I prefer, however, to use the groove *c*, as it enables me to place greater or less number of rods on a support, to change their locations on their support with reference to each other in order to slightly avoid cross-beams, such as occur in the frames of spike-harrows, or to adjust the teeth of an agricultural implement with greater nicety with reference to their trailing. This method of mounting rods on a support also enables me to avoid perforating it, which hitherto has been objectionable.

15 One very important feature of this invention is that when the rod and saddle are adapted to rock the spring also rocks relatively to the support on which it is mounted, thus affording a long range of movement at the free end of the rod, with only a slight expansion of the spring additional to that required to locate it on its support, thus avoiding overtaxing the spring and also enabling the manufacturer to secure a maximum movement 20 for the rod with a minimum length of spring. Said construction is not only economical, but it also permits implements or articles, such as the beams of a spike-harrow, to be rocked for adjusting the pitch of the teeth without the 25 spring coming in contact with the ground. It also enables harrows embodying this construction to be piled up in small space for storage or transportation.

It will be seen that the spring encircles the 30 support *C* and covers the fastened end of the rod which projects from its support, and when used with spike-harrow teeth furnishes such a protection that neither the operator nor team need be injured by their upper ends.

40 The spring not only has a pivotal motion in the groove *c*, but also has a slight pivotal movement at its contact-point *a* with the rod, thus assisting to increase the range of movement without overtaxing the spring.

45 The saddle projection *b* is made slightly tapering, and the pressure of the spring drives the wedge of the saddle into the channel, so as to fit closely not only when new, but to also take up wear of the parts, so that the 50 rod will always be held firmly, even after long use, relatively to its support, and so that wrenching strains against the rod-fastenings, such as are incident to turning a spike-harrow around when its teeth are in the ground, 55 are thus overcome.

One size and shape of saddle will receive and retain various sizes and shapes of rods, the spring adapting itself to them all and having sufficient range of movement to 60 brace and bite into any size or shape of rod that will enter the saddle and also having sufficient power to hold against undesired movement therein any rod that will enter the saddle.

65 When used for agricultural implements, the construction of saddle and rod previously described gives the user a choice of teeth,

enabling a variety of work to be done with one implement.

Where my joint is applied to an article or 70 implement having many rods—for instance, a spike-harrow—each rod or tooth thereof may rock on a center independent of others, so that rubbish will work out of a harrow better than if constructed otherwise, and although 75 each rod may be rigid in itself, retaining the qualities desired for certain work, yet in another sense it becomes a spring, and therefore a small-sized rod held to its work by an individual spring therefore will stand hard service 80 better than a larger one when made to be unyielding.

When it is desired to construct a joint so that the spring *D* will be maintained at a right angle to the length of support *C*, I form 85 a socket or slot, through which the spring passes, as shown in Figs. 1 and 3. The spring will, however, perform its functions if its body portion is not maintained at a right angle to the beam.

90 By reference to the drawings it will be seen that the saddle forms a wedge between itself and the channel-support, and any tendency of the rod to move transversely and backwardly relative to the support and beyond its predetermined limits causes the saddle and support to nip together, as shown at *y* and *z*, Figs. 1, 2, and 3, and prevent undue movement of the parts relative to each other. The angular or transverse projections 100 *R R R R* of the saddle interlock with beam *C*, through the lines *xz*, (shown in Figs. 3 and 1,) and assist the wedge action of the saddle in overcoming oblique or twisting strains thereon. In some instances I make the rod 105 integral with the saddle, as represented in Fig. 15.

110 In the drawings I have shown my invention applied to the usual frames of harrows. The teeth and beams thereof are the prototypes or equivalents, respectively, of the "rods or other members and beams or other supports" first mentioned. However, such application of my invention to harrows is not shown with any intention of in any wise limiting myself 115 thereto, but simply as showing one of the many practical applications of my invention.

120 By the use of my invention I secure an efficient and simple joint between the rod or other member and a beam, pipe, shaft, or other support for said member, and I am enabled thereby to dispense with riveting or the use of screws or bolts, nuts, and other objectionable and expensive devices. Moreover, 125 my joint may obviously be employed in many different places and to subserve many different purposes. For instance, my invention may be used in the manufacture of agricultural implements where it is necessary to secure a rod or tooth to a beam or other support, such as in harrows and hay-tools, although 130 the invention can find advantageous application elsewhere. Consequently I contemplate all the uses to which my invention is appli-

cable and all the forms in which it may be constructed.

While I have described parts suitable for implements such as are shown in the drawings, it is obvious that many changes may be made in their form and proportion and that equivalents may be used without departing from the spirit and scope of my invention and claims.

10. I claim—

1. A joint comprising two parts fulcrumed across each other, each part having a seat for a spring, and a circular spring having portions engaging with said seats and adapted 15 to "lock" them at opposite sides of said fulcrum.

2. A joint comprising a support, a saddle suitably mounted thereon, and a spring having an end adapted to "bite" into the support and also adapted to support the saddle relatively to the support.

25. 3. A joint comprising a support having an open seam, a saddle mounted in the seam, a rod supported by the saddle, and a spring embracing and holding them together in operative relation by its resiliency.

4. A joint comprising a support, a saddle adapted to rock on the support transversely thereto, and a spring hinged relatively to the support and self-gripping said parts together.

5. A joint comprising a support, a perforated saddle, a rod adjustable lengthwise in said perforation, and a spring self-gripping said parts together.

35. 6. A joint comprising a support, a rod and a saddle therefor interlocking with said support, a seat in said saddle, a spring fulcrumed therein and fulcrumed by its other end to the beam, and a retainer for the spring carried 40 by the saddle.

7. A joint comprising a channeled support, a saddle adapted to rock relatively thereto, a rod mounted in the saddle, and a spring, in combination with a projection from the 45 saddle interlocking with the support to prevent "rebound" of the saddle relatively to the beam when returned to its normal position by the spring.

8. In a joint in combination with tongue- 50 and-grooved parts an expandible spring embracing between its ends and holding together under self-reducing spring tension said parts.

9. In a joint a support, a saddle mounted loosely thereon, a rod carried by the saddle, 55 and a spring for binding the saddle to the support, in combination with a double stop co-operating with the support and saddle to limit the rocking of the saddle in opposite directions relatively to the support.

60. 10. A joint comprising a support, a saddle locked loosely thereto in one position by its configuration and having a projection thereon adapted to lock it to the support in another position, and a spring embracing said parts 65 and holding them in contact.

11. A joint comprising a support, a spring

mounted thereon, a saddle having an opening therein adapted to receive a rod and also having a notch therein adapted to receive an end of a spring, and a ledge between said openings.

12. A joint comprising a saddle, a support therefor, and an embracing-spring supporting the saddle crosswise relatively to said support and self-maintainable thereon by pressure of the spring.

13. A joint comprising imperforate rod A, perforated saddle B holding said rod, imperforate support C supporting said saddle, and spring D self-gripping the parts together.

14. A joint comprising a support, a saddle thereon, a rod carried by the saddle, and a spring embracing the support and the rod between and by cornered portions of the spring.

15. A joint comprising a support, a saddle rocking on a projection of the support as its center of motion, a spring engaging with the support and saddle and adapted to press them together in combination with means adapted to stop the rocking movement of the saddle at a predetermined limit relatively to the support.

16. A joint comprising a support, a saddle interlocking therewith, a rod carried by the saddle, and a spring operatively engaging and holding the parts to each other and covering an end of said rod.

17. In a joint a support having a proportionately large channel on one side and a relatively small channel on an opposite side thereof, in combination with a spring attached in one of said channels and also holding a rod-carrying saddle in operative position on the support.

18. In a joint a saddle adapted to rock on a support therefor said support and a rod carried by the saddle, in combination with a spring seated on the support and adapted to maintain the free end of the rod at two predetermined angles relative to said support.

19. A joint comprising a channeled support, a saddle adapted to rock on a limb of the support, a notch L, in the saddle adapted to interlock with said limb, and a spring embracing the support and saddle.

20. A joint comprising a saddle, a support therefor interlocked therewith at their bearing against each other, and a spring embracing the support and saddle and surrounded 120 between its ends by the saddle.

21. A joint comprising a support, a saddle carried thereby rigidly in one direction transversely thereto and flexibly thereto in the opposite direction, and a spring which self-grips 125 the saddle to the support.

22. A joint comprising a saddle-support, a rod-carrying saddle loosely engaging with said support, and a spring self-gripping said parts together.

23. In a joint a support for a saddle, a saddle mounted thereon, a rod carried by the

saddle, and a spring self-gripping said parts together, the spring having rocking movement on an integral end thereof and in line with its spring action.

5 24. In a joint a spring self-gripped to a saddle-carrying support and to a saddle thereon, and a rod carried by the saddle, a portion of one end of the spring being maintained out of contact with the part gripped by the spring.

10 25. In a joint a spring self-gripped by its end to a support therefor and to a rod-carrying saddle mounted on said support, the spring having one of its ends constructed at an angle relatively to its body portion.

15 26. In a joint a spring self-gripped by one of its ends to a support and retained by its other end by a saddle on the support, in combination with a rod held from endwise movement relatively to the saddle by the saddle 20 end of the spring "biting" into said rod.

25 27. A joint comprising an operative mechanical structure consisting of an expandable spring self-gripped on and with two parts of said joint which are thereby loosely hinged into each other, one part thereof being adapted to rock relatively to the other and one end of the spring being pivotally held on the stationary part and the other end traveling in concert with said rocking part.

30 28. A joint comprising a circular expandable spring having an opening therein, and two parts of said joint having a tongue-and-grooved metal bearing rocking against each other at a point within the circle formed by 35 the metal of the spring which assembles and self-grips said parts together.

29. A joint comprising a circular expandable spring having an opening therein, and two metal parts of said joint arranged between 40 the ends of the spring, and a rod gripped at a corner thereof by the spring and thereby held in and relatively to one of said metal parts.

45 30. A joint comprising two metal parts and a spring connecting itself and said parts together at four fulcrum-bearings two of which have configuration adapted to interlock together.

31. A joint comprising two metal parts interlocked together transversely relatively to 50 each other, each having at a side thereof a seat for a spring, in combination with an expandable spring fitting into said seats.

32. In a joint a rod-carrying saddle rocking within limits on a projection of a support 55 for the saddle and "nipping" simultaneously with opposing portions of said support at a predetermined stage of said rocking movement, in combination with a spring engaging 60 with the saddle and support.

33. A joint comprising a rod-carrying saddle laterally adjustable on a support therefor, and a circular spring self-gripping the parts together.

65 34. In a joint, a rod-carrying saddle, laterally adjustable on a support, said support

and a circular spring self-gripping the parts together at a fulcrum-bearing located within the circle of the spring, one end thereof being adjustable relatively to said fulcrum-bearing. 70

35. A joint comprising a saddle, a three-sided support therefor, two of said sides abutting against the saddle, and a spring self-gripped to the saddle and to the third side of said support.

75 36. A joint comprising a rod-carrying saddle and a support therefor said parts having interlocking wedge portions, in combination with a spring pressing the inclined surfaces of said wedge portions into close contact.

80 37. A joint comprising a rod-carrying saddle and a channel-support therefor, the saddle having bracing lateral bearing portions between it and the support, and a spring self-gripping said lateral bearing portions into 85 contact with the support.

38. In a joint a rod-carrying saddle, a support therefor having at one side thereof an interlocking hinge connection with the saddle and having an opposite side thereof inclined relatively to the saddle, in combination with a projection on the saddle which may "nip" with said inclined surface as the saddle is being rocked on its hinge. 90

39. A joint comprising a rod-carrying saddle having a projection from one side thereof at a right angle thereto, a support for the saddle having a channel with right-angled interior walls adapted to impinge on the saddle projection located between said walls, and a circular spring having an end thereof engaging with the channel-support and its other end engaging with the saddle. 95

40. A joint comprising a rod-carrying saddle located between the limbs of a channeled support and adapted to rock on one of said limbs, and a spring engaging the saddle at a point relatively between the limbs of the channel and also engaging the support at a point relatively between the limbs thereof but on the side opposite to the saddle, in combination with a projection from the saddle adapted to impinge upon the exterior of said support at a point between the saddle-hinge and the spring's engagement with said support. 105

41. A joint comprising a saddle-carrying support, a saddle thereon, a cornered rod maintained by the saddle diamondwise relatively to the support, and a spring self-gripping the parts together. 110

42. A joint comprising a support having one exterior side thereof rounded and the opposite side thereof constituting a flat bearing, a rod-carrying saddle abutting against said flat bearing, and a spring self-gripping said 115 parts together.

43. In a joint a rod-carrying saddle, a support therefor, and a circular spring having an end thereof loosely seated in the saddle and its other end engaging a seat therefor on the support, said spring adapted to be rocked on its seated end and expanded simultaneously. 120

ously with said rocking movement until its free end engages with a seat therefor on the support.

44. A joint comprising a rod-carrying saddle, a support therefor, and a circular spring having an end seated in the saddle and its other end seated on the support, in combination with retainer b^2 and projection b^4 .

45. A joint comprising two separate metal parts placed in abutting interlocking contact with each other, and a self-gripping spring embracing within said circle the said abutting portions, the metal of the spring "biting" into the metal of said parts.

46. A joint comprising a rod-carrying saddle and a support therefor locked loosely thereto so that the saddle may rock transversely relatively to its support in one direction only, and a self-gripping spring holding said parts in normal working position under spring tension and adapted to follow the rocking movement of the saddle past its center of motion and then to hold the saddle out of normal position under spring tension.

47. A joint comprising a rod-carrying slotted saddle adapted to rock relatively to a support therefor, in combination with said support and a spring in the slot adapted to rock on an end thereof and self-gripping the saddle and support into direct contact with each other.

48. A joint comprising two interlocking parts one held from movement and the other having relative movement assembled and maintained under spring tension in direct contact with each other by a self-gripping spring abutting against opposing portions of said parts.

49. A joint comprising a rod-carrying saddle adapted to rock on a support therefor, said support and a self-gripping spring uniting said parts and having one end thereof fulcrumed to the support and its other end adapted to follow the rocking movement of the saddle.

50. In a joint a rod-carrying saddle, a support therefor having an exterior surface adapted to turn in a bearing therefor adjacent to the saddle, and a spring self-gripping the saddle and support together.

51. A joint comprising a support having two limbs and a member held transversely relatively to said limbs by a spring.
